1 Claim. (Cl. 287—117)

In drilling deep holes in earth or rock a drill rod is often used comprising a number of extension rods threaded at both ends and interconnected by a coupling piece at each joint. In the use of such threaded extension rods it frequently occurs that the thread is worn out or damaged. In percussion drilling the rod breaks at the diminished threaded section because of fatigue stresses. Such damage or rupture of the threaded section permits further use of the extension rod after re-threading the broken end. This re-threading is, however, difficult to perform at the place where the drill is used and the rod generally has to be taken to a workshop for re-threading.

The present invention aims at an improvement in this respect by manufacturing the extension rods with an extra threaded portion adjacent to the end thread and having the same length as the end thread. When the end thread breaks or is worn out it is only cut away and the extra thread forms the new end thread. The only operation needed is to cut off the worn out thread portion and to finish the end surface so that the rods have full end contact with each other at the joint. These operations generally may be performed at the drilling site. The more complicated pre-threading is performed in advance at the factory in making the drills. This involves an increase of the manufacturing cost but a reduction of the total cost, as all the necessary threading is performed in one step, when the rod is mounted in the threading machine. Further the cost for transporting the rod between the drilling site and a workshop for re-threading is eliminated. This contributes the further advantage that the quantity of drill equipment necessary for a certain job is reduced, as none of it has to be sent away for re-threading, thereby reducing also the investment costs and simplifying the transport problem in isolated drilling sites.

Further details and advantages of the invention appear from the following specification and the accompanying drawing in which

FIG. 1 is an elevational view, partly in section of a joint of two extension rods having a circular cross section and external threads.

FIG. 2 is an elevational view of a joint of a hexagonal rod having an external thread.

FIG. 3 is an elevational view of a modification of the joint shown in FIG. 2.

FIG. 4 is an elevational view, partly in section of an embodiment with circular rods having internal threads.

FIG. 1 shows two extension rods 10 and 11 forming elements of a drill rod of the kind generally used for percussion drilling. The extension rods have circular cross sections and are externally threaded by outer threads 13 and 14 respectively and coupled together by a coupling sleeve 12 having an internal thread 15. The rods abut against each other at the end surfaces 16 and 17 respectively, which should be plane and perpendicular to the drill axis in order to obtain full contact. This is very important in percussion drilling, where great forces are transferred between the rods and bad end surface contact causes relatively great losses of drilling energy.

At the ends of the threads 13 and 14 that are remote from the ends of the rods there are unthreaded portions

18 and 19 respectively which form stops for the coupling sleeve and hold the sleeve in a position that is symmetric with relation to the abutment surfaces 16 and 17. The length of the coupling sleeve is less than the total length

5 of the threads 13 and 14, so that there is enough room for the coupling sleeve between the stops 18 and 19 in order to ensure the full abutment between the ends 16 and 17. Beyond the abutments 18 and 19 each of the extension rods has a second thread 20 and 21 respectively having the same length as the threads 13 and 14. The abutment portions 18 and 19 thus form a short separate portion between the threads. With extension rods having a circular cross section as in the present embodiment, it is suitable to provide the rods with wrench grips 22 and 23 respectively in order to facilitate the turning of the rods when they are being screwed into the coupling sleeve. The abutments 18 and 19 have preferably the same cross section as the rods and they can be provided with similar wrench grips if desired. 24 is a flushing channel.

10 If for instance the thread marked 14 breaks, the rod 11 is cut off at the section A—A and the end is finished to a plane surface that is perpendicular to the drill axis. As the thread 21 is similar to the discarded thread 14, 15 the rod 11 can now be connected to the coupling sleeve by the thread 21. The rod 10 can be cut off and reconnected in the same way using the thread 20 for the connection.

18 The portions 18 and 19 are suitably integral with the 20 rod and have the same cross section as the rod, which 25 means that in making the two threaded portions these portions 18 and 19 are left unworked between the threads. It is also possible to make a continuous thread 30 having the length of the two threads together but in this 35 case a separate abutment stop is placed on the thread in order to determine the position of the coupling sleeve.

28 In FIG. 2 is shown a similar joint for hexagonal rods. The extension rod 30 is screwed to a coupling sleeve 31 and has at its end a thread within the sleeve (not shown). 30 Adjacent to said end thread is an abutment portion 32 having the same hexagonal cross section as the rod and adjacent to the abutment portion 32 there is a second 35 thread 33.

38 FIG. 3 shows an extension rod 34 which is slightly 45 modified in comparison with FIG. 2. The sleeve 35 is attached to an end thread (not shown), and the abutment stop 36 has a circular cross section. At the end of the 50 second thread 37 there is a short portion 38 having a circular cross section.

55 The invention can also be used for extension rods having internal threads as shown in FIG. 4. Two rods 40 and 41 forming elements of a drill rod are provided with axial end bores having internal threads 42 and 43 respectively close to the open ends of the bores and 60 second threads 44 and 45 respectively close to the bottoms of the bores. Between the two thread portions 42—44 and 43—45 in each bore there is an unthreaded portion 46 and 47 respectively. The rods are coupled together by an externally threaded tap 48. When the threads 42 and 43 or either of them is worn out or otherwise 65 made unusable the rods are cut off at the cross sections B—B and C—C, the abutment surfaces are finished, and the threads 44 and 45 are used for coupling the rods together.

70 The invention is especially useful for common percussion drill extension rods having a thread on each end but can also be used for such parts of the drill rod that have a thread only at one end, as a drill rod having a drill bit integral therewith at one end. It is of course possible also to use the invention in connection with other kinds of drills as rotary drills. Other obvious

variations of the described embodiments can be made within the scope of the following claim.

We claim:

In a drill rod, an extension rod having a long unthreaded portion comprising the main and central part of the extension rod, at least one end portion being externally threaded and having two consecutive threads having the same pitch, length and diameter, said threads being separated by an integral short unthreaded portion having a cross-sectional area substantially at least equal to the cross-sectional area of said long unthreaded portion, said long unthreaded portion and said short unthreaded portion each having an external dimension at least equal to the external dimension of said threads, the outermost of said threads extending to the end of said extension rod and being adapted to receive an internally threaded sleeve for coupling said extension rod to a second extension rod, the end surface of said extension rod being adapted to abut against a similar surface on said second extension rod, said short unthreaded portion forming an abutment stop for said sleeve when screwed onto said outermost thread, the innermost of said threads being

5

adapted to receive said sleeve for said coupling purpose after cutting off said outermost thread together with said short unthreaded portion, said long unthreaded portion serving as an abutment stop for said sleeve when screwed onto said innermost thread.
